CLAIM

The ornamental design for footwear, as shown and described.

DESCRIPTION

FIG. 1 is a front perspective view of footwear;

FIG. 2 is a front view thereof;

FIG. 3 is a back view thereof;

FIG. 4 is an inner side view thereof;

FIG. 5 is an outer side view thereof;

FIG. 6 is a top view thereof; and

FIG. 7 is a bottom view thereof.

FIG. 8 is a front perspective view of the footwear of FIGS. 1-7, with the textile band removed from the upper perimeter for clarity of disclosure;

FIG. 9 is a front view thereof;

FIG. 10 is a back view thereof;

FIG. 11 is an inner side view thereof;

FIG. 12 is an outer side view thereof;

FIG. 13 is a top view thereof; and,

FIG. 14 is a bottom view thereof.

The broken lines in the drawings represent unclaimed environmental subject matter.
